UNITED STATES PATENT OFFICE.

JOHN E. LEEPER, OF GODFREY, ILLINOIS.

IMPROVEMENT IN THE CONSTRUCTION OF RAILROAD-CARS.

Specification forming part of Letters Patent No. 147,777, dated February 24, 1874; application filed May 19, 1873.

To all whom it may concern:

Be it known that I, JOHN E. LEEPER, of Godfrey, Madison county, and State of Illinois, have invented an Improved Construction of Cars, of which the following is a specification:

This invention presents certain improvements on the patent granted to me of date June 20, 1871, and being numbered 116,069.

The design of this invention is to form either a freight, refrigerator, passenger, or similar car or vehicle, and, therefore, its improved construction relates to a novel formation of the car-body proper.

Of the drawing, Figure 1 represents a perspective view of the car with parts broken away. Fig. 2 is a transverse sectional elevation. Fig. 3 is a bottom plan of part of the car, and to Fig. 4 as a detail bottom plan, showing manner of securing ribs to sills.

The platform of the car is composed of the usual outer sills A A¹ and flooring properly braced. It is desirable, to achieve my design, to provide the bottom with additional inner or bottom sills A² A³ A⁴ A⁵. (See Figs. 2 and 3.) Not only is thus a firmer and securer bottom made, but between the sills thus provided the ribs and the suspended chambers are placed. The bottom or side sills A A² A¹ A³ are, therefore, placed and secured some distance apart to receive the ribs that form the skeleton-body of the car. B are the frames or ribs, consisting of iron bars united, with a strip of wood, b, intervening. As apparent, the shape of the rib can be either a U or E (angle) shape. The ribs B, being bent circular, tubular, or similar approximate shape, are relatively set apart, and surround the sides of the car. Further, the ribs B pass down between two outer sills, A A² A¹ A³, and are held in place by bolts. (See Figs. 3 and 4.) The outer and inner shells of sheet metal a a' are bent over the ribs, and riveted or bolted

thereto. The inner shell a' closes the interior of the body to the floor, Fig. 2, while the outside shell passes over the bottom sills A A¹. (See Figs. 1 and 2.) The ends of the car are simply double shelled or lined. The inner shell a' of the body may be part of wood and part sheet metal. Air-passages b', Fig. 3, are thus left between the two outer sills each side of the car, or between every two ribs throughout the length of the car, for ventilating purposes. Here it will be noticed a most complete ventilation is obtained by the air passing up from the bottom and being admitted into the air-spaces b', rising up into same between the inner and outer shells or walls of the car, and thus surrounding same. C are doors either side of car, and may be arranged to slide in guides c; or they can be hinged doors. D, Figs. 2 and 3, are chambers, consisting of sheet metal or plates of a circular form, suspended and secured between the sills A² A⁴ and A³ A⁵, the object of the chambers D being either serviceable for hot-air chambers or water-tanks. In the top of the car, for refrigerating purposes, an ice-trough, d, is attached. From the trough d proper pipe-connection can be made at either end, leading to a chamber, D, below. E is a running-board, with banisters e on each side, and secured properly to top of the car. (See Fig. 1.)

What I claim is—

The combination of the side sills A A¹ A² A³, chamber D, ribs B, and shells a a', to form a ventilating-space, b', and to secure a direct introduction of outside air around the body of the car and within the walls thereof, as shown and described.

In testimony of said invention I have hereunto set my hand in presence of witnesses.

JOHN E. LEEPER.
